CLOTHESPIN

Arthur C. Potter, 68 Addison Road, Manly,
New South Wales, Australia

Filed Apr. 7, 1964, Ser. No. 79,384

Claims priority, application Australia Oct. 8, 1963

Term of patent 14 years

(Cl. D17—6)

FIG. 1.

FIG. 2.

FIG. 3.

FIG. 4.

FIGURE 1 is a front elevational view of a clothespin, showing my new design, the opposite or rear face being the same in appearance.

I claim:

The ornamental design for a clothespin, substantially as shown and described.
